UNITED STATES PATENT OFFICE.

JOHN G. SODERBERG AND WALTER H. WAKEFIELD, OF WORCESTER, MASSACHUSETTS,
ASSIGNORS TO CROMPTON & KNOWLES LOOM WORKS, OF WORCESTER, MASSA-
CHUSETTS, A CORPORATION OF MASSACHUSETTS.

TUBE FRAME FOR AXMINSTER LOOMS.

Application filed June 22, 1923. Serial No. 647,179.

To all whom it may concern:

Be it known that we, JOHN G. SODERBERG and WALTER H. WAKEFIELD, both citizens of the United States, residing at Worcester, in the county of Worcester and State of Massachusetts, have invented a new and useful

Tube Frame for Axminster Looms, of which

the following is a specification.

This invention relates to tube frames of the type generally employed on wide Axminster looms, and an object of the invention is to utilize ordinarily wasted material for securing the spool bearing and chain engaging brackets to the tube frames in such a way as to permit the construction of the brackets with less material but with no loss of strength.

The tube frames ordinarily used in weaving wide Axminster rugs are commonly formed of tubular metallic bars rectangular in cross-section. The ends of each bar are provided with brackets which are formed with spool bearing and chain engaging portions and each bracket, as usually constructed, carried a pair of parallel arms which extend into and are secured to the bar. One of these arms is usually made from a separate piece which must be stamped out by an additional operation and welded or otherwise secured to the bracket. The arms so formed represent extra stock and labor and it is one object of our invention to eliminate the extra expense incident to such a construction.

The rough bars from which the tube frames are made are usually supplied somewhat longer than the finished frame is to be so that the ends may be accurately finished and another object of our invention resides in making use of a part of such stock as would otherwise be wasted.

With these and other objects in view our invention resides in the combination and arrangements of parts hereinafter described and set forth in the appended claims.

In the accompanying drawings, wherein three forms of our invention are shown,

Fig. 1 is an end view of a tube frame embodying our invention,

Fig. 2 is a vertical section taken on line 2-2 of Fig. 1,

Fig. 3 is a perspective view of one end of a tube frame bar formed according to our invention,

Fig. 4 is a horizontal section taken on line 55 4-4 of Fig. 2,

Fig. 5 is a view similar to Fig. 2 but showing a modified form of the invention,

Fig. 6 is a horizontal section taken on line 60 6-6 of Fig. 5,

Fig. 7 is a view similar to Fig. 2 but showing another modification of the invention, and

Fig. 8 is a horizontal section on line 8-8 65 of Fig. 7.

In the form of the invention shown in Figs. 1-4 the bracket 10 is formed with the usual spool bearing 11 stamped therefrom and arranged to receive gudgeon 12 of spool 13. Another portion of the bracket is offset from the body thereof to form the chain engaging tongue 14 while the lower end of the bracket is bent to form an arm 15 which is countersunk as at 16. Screws 17 pass through the tubular bar 18 and are threaded into countersunk parts of the arm 15. A leaf spring 19 is held to the bracket by a screw 20 and has the upper end thereof passed through slot 21 which is formed in the bracket when bearing 11 is stamped therefrom. The matter thus far described is of the usual construction.

Our improvements reside in means for giving additional support to the bracket such support as shown herein being applied 55 near the upper part of the tubular bar 18. As shown in Fig. 2 we form the bar with a lip 22 integral therewith and bend said lip so that it will be parallel to the vertical or body portion of the bar, the lip in this instance being bent upwardly from the bar. Screw 23 is then passed through the bracket and threaded into the lip 22, in which position it may be held tightly by lock nut 24. The use of the lock nut is made possible because both ends of the screw are accessible 90 from without the bar 18.

In looms employing tube frames of considerable length, it is desirable to have a bracket somewhat stronger than the one previously described and in the following modifications to be described the bracket is shown

as reinforced to meet the requirement of longer tube frames.

In the form of the invention shown in Figs. 5 and 6 the bracket is formed substantially as in the preferred form, with the exception that the spool bearing is omitted. This latter is provided by making the lip 31 on bar 32 long enough to extend to the spool gudgeon, thus permitting the bearing 10 for the spool to be formed integrally with the bar. The arm extending from and projecting into the bar is held to the latter in a manner similar to the preferred form, and the body of the bracket is held to the lip 15 31 by means of screws 33.

In the modification shown in Figs. 7 and 8 the bracket 40 is similar to bracket 30 but the tubular bar 41 has formed integral therewith a relatively short lip 42 provided preferably with a clear hole to receive screw 43. The spool bearing is formed of a separate stamping 44 offset as at 45 to overlap the lip 42 and threaded to receive the aforesaid screw 43. A second screw 46 may be used 20 to secure the bearing to the bracket and the upper end of the bearing member may be perforated as at 47 to receive the spool gudgeon. It is not necessary that the bearing member 44 be removable from the bracket, as the latter may be removed from the tubular bar by removing screw 43 and screws 48 and then sliding the bracket parallel to the lip 42, until the end of the spool bearing which overlaps the lip is disengaged 30 therefrom. The bracket can then be removed and another one substituted therefor.

From the foregoing it will be seen that a portion of the tubular bar ordinarily wasted is employed in such a way as to afford a support for the bracket, and because of this construction the bracket can be made with less material than heretofore.

Having described our invention, it will be apparent that changes and modifications can 40 be made therein by those skilled in the art without departing from the spirit of the invention; and we do not wish to be limited

to the details disclosed herein, but what we do claim is:

1. In a tube frame for Axminster looms, 50 a hollow metallic bar, one wall of said bar being extended and bent at right angles thereto to form an ear, a chain engaging bracket member having a portion extending within the bar and secured to that portion of the hollow bar opposite the side from which the ear is bent, a spool supporting member having a portion thereof extending along the chain engaging member and having that portion thereof adjacent the bar offset and engaging the inner face of the ear, the chain engaging member engaging the outer face of said ear so that said ear lies between the members, and means to secure the members together and to the ear, 60 said means including a removable device extending through the members and the ear and threaded into the spool supporting member.

2. In a tube frame for Axminster looms, 70 a hollow metallic bar, one wall of said bar being extended and bent at right angles thereto to form an ear, a chain engaging bracket member having a portion extending within the bar and secured to that portion of the hollow bar opposite the side from which the ear is bent, a spool supporting member having a portion thereof extending along the chain engaging member and having that portion thereof adjacent the 75 bar offset and engaging the inner face of the ear, the chain engaging member engaging the outer face of said ear so that said ear lies between the members, and means to secure the members together and to the ear, 80 said means including a removable device extending through the members and the ear and threaded into one of said members.

In testimony whereof we have heretofore 85 affixed our signatures.

JOHN G. SODERBERG.
WALTER H. WAKEFIELD.
